UNITED STATES PATENT OFFICE.

JOSEPH F. SEIBOLD AND GEORGE H. LEPPERT, JR., OF INDIANAPOLIS, INDIANA.

AUTOMATIC RAILWAY SAFETY APPLIANCE.

1,178,824.

Specification of Letters Patent. Patented Apr. 11, 1916.

Application filed November 22, 1913. Serial No. 802,398.

To all whom it may concern:

Be it known that we, JOSEPH F. SEIBOLD and GEORGE H. LEPPERT, Jr., citizens of the United States, residing at Indianapolis, in the county of Marion and State of Indiana, have invented a new and useful Automatic Railway Safety Appliance, of which the following is a specification, reference being had to the accompanying drawings and to the letters and figures of reference marked thereon.

This invention relates to appliances for the safe control of railway trains or cars and to prevent collisions, the invention having reference more particularly to means for automatically stopping a railway train or a car, especially in case stop signals are disregarded by the engineer or the motorman thereof, the invention being adaptable for use in connection with either steam or electrically operated trains or cars.

The object of the invention primarily is to provide automatic safety appliances which shall be so constructed that action shall be positive and reliable and not be dependent upon human agency or control, to the end that life and property may be saved through avoidance of collisions of the trains with other trains or cars.

A further object of the invention is to provide automatic railway safety appliances of such construction as to be free from electrical or other complications and uncertainties of action and which shall be of simple construction, durable and economical in use.

A still further object of the invention is to provide a safety appliance which may be adapted to be used in connection with various types of block signal systems or with switch operating apparatus, for the purpose of positively stopping the train or cars in case a signal indicates that the train or cars should stop in order to avoid danger.

With the above mentioned and other objects in view, the invention consists in a projectable block or device adapted to be supported on the roadway and to be connected either with block signals or with switch operating apparatus; the invention consisting also in apparatus adapted to be carried by a locomotive or a motor car and into contact with the block when the latter is projected and to cause the air-brakes of the locomotive or car to be applied and also to cause the

power controller, such as the throttle-valve lever or controller lever, to be operated so as to shut off the propelling power, the whole apparatus being designed to promptly operate so that ample time shall be allowed for effective operation of the controlling brakes of the train or car.

The invention consists also in the novel parts and in the combinations and arrangements of parts as hereinafter particularly described and further defined in the accompanying claims.

Referring to the drawings, Figure 1 is a side elevation of the invention connected with the air-brake system of a locomotive and train, the latter being indicated by dotted lines, as illustrating the general arrangement and adaptability of the invention; Fig. 2, a top plan of the tripping or controlling apparatus adapted to be carried by the locomotive or car; Fig. 3, an end elevation of the tripping apparatus; Fig. 4, a diagrammatic view comprising elevations of the various features of a train controlling apparatus and section of railway with which the invention is connected to illustrate the complete arrangement of all the essential elements necessary to the application and operation of the invention; Fig. 5, a vertical section on the line A A in Fig. 2; Fig. 6, a sectional elevation on the line B B in Fig. 2 in which controlling valves are shown in connection with the tripping apparatus; Fig. 7, a perspective view of one of the parts of the tripping apparatus; Fig. 8, a perspective view of the trip-lever comprising a part of the apparatus; Fig. 9, a fragmentary section on the line C C in Fig. 6; Fig. 10, a section on the plane of the line D D in Fig. 9; Fig. 11, a top plan of a section of railway track and a semaphore signal with which the signal station portion of the invention is connected; Fig. 12, a cross section of the railway and the signal station in elevation connected therewith; Fig. 13, a fragmentary view showing a portion of the locomotive boiler and throttle-valve controlling apparatus connected therewith; Fig. 14, a section on an enlarged scale of parts of the controlling apparatus; Fig. 15, a section on the line E E in Fig. 11; Fig. 16, a section on a plane of the line F F in Fig. 15; Fig. 17, a section partially broken away on the plane of the

line G G in Fig. 16; Fig. 18, an inverted plan view of the projectable block, and Fig. 19 is a top plan of the base and guide of the block.

5 Similar reference characters in the different figures of the drawings indicate corresponding elements or features of construction herein referred to.

In practically carrying out the objects of the invention a suitable frame or base plate 1 is provided which is suitably adapted to be supported under the deck of a locomotive or elsewhere as may be preferred, preferably in horizontal position, and it is provided on 10 its top with two journal boxes 2 and 3 in which a shaft 4 of suitable length is rotatively mounted, the shaft having a squared end portion 5 whereby it may be turned in its bearings. A disk 6 is secured fixedly to 15 the shaft and has a transverse notch 7 in its periphery, an arm 8 being also fixedly secured to the shaft adjacent to one of the journal boxes. Another arm 9 is fixedly secured also to the shaft for controlling valves, 20 as will further appear. The shaft 4, when of extensive length, is preferably provided with a journal box 10 having a stand or hanger 11 which may be variously supported for steadyng the shaft adjacent to the arm 9. In some cases the shaft may be relatively 25 short and the arm 9 may be arranged near to the journal box 3. The plate 1 has a suitable stand or stands 12, 12', thereon, fixedly supporting a spring-box 13, which for convenience is cylindrical and has a head 14 in one end in which is a central guideway 15 through which a rod 16 movably extends. The rod is connected by means of a pivot 17 to the arm 8 and is provided with a head 18 that is movable in the spring-box, a coil 30 spring 19 being seated under compression between the heads 14 and 18, the spring being designed to turn the shaft 4 and consequently move the arm 9 when not restrained. 35 The frame or base plate 1 has also a pivot stand 20 thereon to which a pawl 21 is connected by means of a pivot 22. The pawl is of novel form and has a hook 23 on its free end which may ride on the disk 6 or drop 40 into the notch 7 and hold or lock the shaft 4 in the required position to maintain the spring 19 under compression, the spring being permitted to expand and act when the hook is withdrawn from the notch. A 45 wrench or lever may be connected to the end 5 of the shaft for turning the latter so as to cause compression of the spring. Preferably the pawl 21 is yieldingly held to the disk by means of a spring 24 connected to 50 the pawl and also to the base plate. The under side of the pawl has a straight-faced contact portion 25 presented toward the base plate. The top of the frame or base plate 1 is provided also with two journal boxes 55 26 and 27 in which a pivot 28 is supported

above a slot 29 formed in the base plate through which a trip lever 30 extends. The trip lever is mounted on the pivot 28 and is permitted to oscillate, the lever having a hole 31 therein near its upper end to receive 70 the pivot, and the upper end of the lever preferably is flat and of suitable length so that two projections 32 and 33 are formed that serve as cams to slide against the straight-faced portion 25 for pivotally moving the pawl from the notch of the disk 6. The under side of the plate 1 has two abutments 34 and 35 thereon suitably spaced apart and having guideways 36 and 37 therein respectively in which a rod 38 is slidingly 80 guided. The rod has screw threads 39 thereon on which adjusting nuts 40 and 41 are placed so that they are between the abutments. A coil spring 42 is seated under compression in contact with the abutment 34 and the nut 40, a similar spring 43 being seated in contact with the abutment 35 and the nut 41, so that the springs normally hold the rod yieldingly in mid position, the rod being connected by means of a pivot 44 with 90 a link 45 which is connected by means of a pivot 46 to the trip lever 30. It will be apparent that the pawl is retracted on movement of the trip lever in either direction on its pivot, the lever being returned to and held in mid position by the spring 42 or 43. The frame or base plate 1 is carried at a suitable height above the roadway and the trip lever is designed to extend downward nearly to the plane of the tops of the track 100 rails.

Two cylindrical valve cases or casings 47 and 48 are suitably connected to a common base or bracket 49 whereby they may be suitably supported side by side, the outer side of one casing having a guide-stud 50, the outer side of the companion casing having a similar stud 51 thereon. An operating rod 52 of suitable length is connected by means of a pivot 53 to the arm 9 and has a cross-bar 54 thereon from which two guide arms 55 and 56 extend, the arms having guideways 57 and 58 receiving the studs 50 and 51 respectively, whereby the rod is guided. The casings are provided with heads 59 and 59' 110 respectively that are opposite to the cross-bar, the opposite ends of the casings being provided with heads 60 and 60' respectively. Intermediately of the heads the two casings have partitions 61 and 61' therein in which 120 are passages 62 and 62' respectively. Two valves 63 and 64 are removably seated upon the partitions so as to normally close the two passages respectively, and they are provided with operating stems 65 and 66 respectively 125 that extend through the lower heads of the casings nearly to the cross-bar 54, the heads preferably being provided with packing boxes 67 and 67' respectively. When the rod 52 is moved upward, the bar 54 evidently 130

lifts the valves 63 and 64 from their seats so as to permit the passage of air from the upper to the lower compartment of the respective casings. A pipe 68 is connected 5 with the head 60 for admitting air to the upper compartment of the casing 47, the lower portion of the casing having an aperture or apertures 69, 69', for the escape of the air from the casing. A pipe 70 is connected 10 with the head 60' for admitting air to the upper chamber of the casing 48, and a pipe 71 is connected with the lower chamber or compartment of the casing for the passage of air therefrom.

15 Familiar portions or parts of the locomotive comprise the rear portion 72 of the boiler, the rear portion 73 of the locomotive frame to which a hanger 74 is connected whereby to support the frame or base plate 20 1, and the frame portion 75 to which a cross-bar 76 is connected for assisting to support the plate 1, the frame or base plate being suitably supported so that the lever 30 shall be suspended equidistantly between the two 25 rails of the track. When sufficient space is available the valve casings 47 and 48 may be arranged under the deck plate instead of the position indicated in Fig. 1. The automatic air-brake system comprises the air-pump 77, the main reservoir 78 connected 30 with the pump by a pipe 79, a supply pipe 80 being connected to the reservoir and to the engineer's brake valve 81 with which the train line pipe 82 is connected and in which 35 air pressure is maintained at all times during operation of the train, 83 indicating the line pipe of the engine tender connected with the line pipe 82 by means of a flexible coupling-hose 84, the car line pipe 85 being 40 connected with the pipe 83 by a flexible coupling-hose 86. Each car and tender equipment comprises the auxiliary reservoir 87 and the brake cylinder, 88, the triple valve 89 and connecting pipes 90 and 91. 45 As will be understood, the train brakes are automatically applied when the air pressure is reduced in the train line which causes automatic action of the triple valves so as to admit air under pressure from the auxiliary reservoirs into the brake cylinders. The pipe 68 is connected with the line pipe 82 so that the compressed air is admitted 50 from the train line pipe into the upper chamber of the valve casing 47, and consequently the train line pressure may be reduced so as to cause action of the brakes when the valve 63 is opened and permits the compressed air to pass through and escape from the lower chamber into the 55 atmosphere. The pipe 70 is connected with the main reservoir, preferably by being connected directly to the pipe 80, so that reservoir pressure is maintained in the upper chamber of the valve casing 48 and upon 60 the valve 64 which, on being opened, per-

mits the compressed air to pass into the pipe 71 to be utilized for shutting off the power that is applied in the movement of the train or car.

It will be understood that the throttle-valve of the locomotive is provided with an operating stem 92 which may be variously arranged and in the present case extends through the rear boiler head and is provided with a throttle lever or controlling lever 93 75 that is connected to a suitable support pivot 94, it being understood that when the lever is pushed toward the boiler head the action causes the throttle-valve to be closed and therefore the source of power is shut off. 80

In order to illustrate the application of the present invention, a bracket 95 is supported by the boiler head and supports a cylinder 96 which is provided at one end with a spider or bridge 97 that guides a piston rod 98 having a piston head 99 that is movable in the cylinder, the outer end of the piston rod being provided with a link 100 that is connected thereto by means of a pivot 101 and is connected also to the lever 90 93 by means of a pivot 102, the opposite end of the cylinder being provided with a head 103, so that when compressed air is admitted to the cylinder between the piston head 99 and the cylinder head 103 the piston is forcibly moved and causes the throttle-valve to be closed. A cylindrical valve chest 104 is provided and has on its side a connecting nipple 105 which is secured to the head 103 or otherwise as may be desired to effect 100 connection with the cylinder 96 and provide a port 106 between the cylinder and the valve chest. One end of the valve chest is provided with a head 107 in which is arranged an adjusting screw 108, a piston 105 valve 109 being normally arranged in the opposite end portion of the cylinder and yieldingly held in normal position, by means of a spring 110 arranged between the valve and the adjusting screw, said opposite 110 end portion of the valve chest being connected to the pipe 71 so that compressed air may be admitted into the valve chest which has an exhaust port 111 that permits the air to pass from the cylinder 96 out through the valve chest to the atmosphere, the port 106 normally being uncovered by the valve 109. When the compressed air is admitted into the valve chest the valve is forced beyond the port 106, the result being that the 120 throttle-valve is closed and held in closed position while the air pressure is maintained.

It will be understood from the foregoing that when the operating rod 52 is moved upward by means of the main actuating spring 125 19, both valves 63 and 64 are simultaneously opened with the result that the air-brakes are caused to be applied and the source of power immediately shut off, so that the train or car cannot proceed until the shaft 130

4 is manually turned so as to retract the rod 16 and compress the actuating spring 19, at which time the pawl 21 again engages the disk or wheel 6 and prevents action of the spring.

The projectable block adapted for causing movement of the trip lever 30 preferably comprises a base plate 112 having holes 113, 113', therein to receive securing devices, and 10 an upright guide 114 upon the plate, the middle portion of the guide having an open vertical guideway 115 therein. The guide 114 has recesses 116 and 117 therein on opposite sides of the guideway, the wall of the 15 guide 114 having apertures 118 and 119 extending from the recesses respectively, and two guide sheaves 120 and 121 are mounted in the recesses adjacent to the apertures respectively. A head plate or block 122 is arranged on or above the guide 114 and is provided with a guide bar 123 on the under side thereof that is vertically guided in the guideway 115 and is limited in its upward movement by means of a stop pin 124 secured in the wall of the guide 114 and extending through a slot 125 formed in the guide bar 123. The plate or block 122 is provided with a guide flange 126 that extends about the guide 114 and excludes dust 20 and snow or ice from the interior of the guide. Two coil-springs 127 and 128 are seated in the recesses 116 and 117 respectively and in contact with the plate or block 122 for forcing the plate or head upward 25 into the path of the lever 30. The plate or block 122 is provided on its under side with lugs 129 and 130 to which cables 131 and 132 are respectively connected, the cables extending under the sheaves 120 and 121 respectively 30 and out through the apertures 118 and 119 respectively, a single cable or link 133 being connected to the two cables whereby to draw down or retract the head plate or block 122 so as to not interfere with the lever 30.

145 The base plate 112 is secured upon two rail ties 134 and 134' that support the track rails 135 and 136. The projectable block is arranged midway between the two rails so that the cable or link 133 extends longitudinally relatively to the rails, and a lateral cable or link 137 is arranged so as to extend under one of the rails and is suitably connected with the cable or link 133 so as to be properly guided, preferably by being connected to one arm 138 of a bell crank having another arm 139 connected to the cable or link 133, the bell crank being mounted on a pivot 140 supported by one of the rail ties 134'. The cable or link 137 is suitably 50 guided as by means of a suitably supported sheave 141 so as to have an end portion 142 turned so as to extend parallel with the track rails, said end portion being connected to a cable or rod 143 whereby a semaphore 55 arm 144 mounted on a post 145 is suitably

controlled, as through the medium of a guiding bell crank 146 mounted on the post and connected to the cable or rod 143, and a cable 147 connected to the bell crank and with the arm or signal apparatus 144. The cable or 70 rod 143 is provided with a suitably guided extension 148 which is connected with an operating lever 149 usually mounted in a signal tower 150, or obviously the lever may be otherwise arranged. The relative arrangement is such that the signal arm is normally maintained in proper position to indicate a clear track by means of the cable or rod 43 and consequently the head or block 122 is retracted so that the train or car is 80 permitted to proceed. When the cable or rod 143 is released, the signal arm or appliance moves by the force of gravity or otherwise automatically to stop position requiring the train or car that may be approaching to stop, and since the tension on the cable or rod 143 is released it is evident that the springs 127 and 128 force up the projection or block 122, the same action resulting in case the cable or rod 143 is accidentally broken so that a danger signal is 90 automatically displayed.

It will be understood that various modifications as to structure and arrangement of various elements may be made, and that the 95 safety appliance is applicable to switch operating apparatus and also is adaptable for use in connection with electrically operated cars having a controlling lever and using the "straight air" system of brakes, it being obvious that with such a system of brakes the pipe 68 may be connected with the main reservoir instead of being connected with the train line pipe, and that a pipe may be connected with the aperture 69 and also with the train line pipe 82 so that compressed air may be admitted by the valve 63 to the train line for applying the brake as would be required; and that in case it is desired to apply the brake automatically without shutting off the power, the valve 63 and its connections might be dispensed with and the pipe 71 be connected with the train pipe 82 instead of being connected with the lever controlling appliance. It is also obvious 105 that with the automatic brake system, if it is desired only to apply the brake without shutting off the power, the valve 64 and its connections may be dispensed with. It should be understood also that the safety 110 appliance and supports thereof may be variously modified so as to be carried by an electric motor car and connected with the rheostat or electric controller lever instead of being connected with the throttle-lever 115 120 93. It will be understood also that the projectable block whereby the trip lever 30 is moved will be arranged on the roadway at suitable distances from the block signal or railway switch, so that in case of necessity 125 130

for stopping to avoid accident ample time is allowed in which to permit the brakes to successfully operate.

It should be understood that in some cases the semaphore arm may be counterbalanced as shown so that the arm is raised to indicate danger and requires to be pulled to safety position, as indicated in the drawings.

In practical use the signal device is properly set as is customary when the train should be stopped, and if the signal is heeded by the engineer or motorman of the approaching train or car the stop is made before reaching the projected stop block that is designed to cause movement of the trip lever. When the track is clear or danger removed so that the train may proceed, the danger signal is moved to safety or to indicate a clear track and at the same time the block is retracted, permitting the train or car to proceed. In case the signal is unheeded or not observed the engine or car proceeds until the trip lever 30 comes into contact with the head 122, whether moving forward or backward, with the result that the lever is moved on its pivot sufficiently to pass over the block and lift the pawl 21 so as to permit the spring 19 to act, as illustrated in Fig. 4, resulting in the prompt application of the brakes and stopping of the train or car through the means hereinbefore described. After the train or car has been stopped, it cannot again be started until the brakes are released after resetting of the shaft 4 and the appliances connected therewith.

The signal station feature of the invention located on the trackway, which may not be herein claimed, forms the subject of a divisional application for Letters Patent, filed June 13, 1914, Serial Number 844,957.

Having thus described the invention, what is claimed as new is—

1. A railway safety appliance including a train pipe for conducting compressed air, a valve casing having a chamber in communication with the train pipe, a safety valve movably mounted in the casing for controlling the passage of air through the chamber, the valve having an operating stem, a supported base, a shaft rotatably mounted on the base and having an arm and also a disk fixed thereon, the disk having a notch in its periphery, an operating rod pivotally connected to the arm and extending to the valve stem for opening the valve, a supported actuating spring provided with a device connecting the spring with the shaft, the spring normally acting to rotate the shaft in one direction to open the valve, a pawl pivotally supported on the base and adapted to enter the notch to restrain action of the spring, and a trip lever pivoted to the base and adapted for engaging and retracting the pawl.

2. A railway safety appliance including a movable controlling lever, a supported cylinder, a piston movable in the cylinder and operatively connected with the lever, a valve chest connected with the cylinder, a valve in the chest and movable to open communication between the chest and the cylinder, a spring in the chest engaging and normally holding the valve in closed position, a compressed-air reservoir, a supported base, a shaft rotatably mounted on the base and having an arm fixed thereon and also a latch device, an operating rod connected to the arm, a supported valve casing having communication with the reservoir and the valve-chest, a safety valve movably mounted in the casing for controlling the passage of air through the casing and having a stem extending to the operating rod for opening the valve, a supported actuating spring operatively connected with the shaft to normally rotate the shaft in one direction for actuating the rod, a pawl movably mounted on the base and adapted to engage the latch device to restrain action of the spring, and a trip lever pivoted to the base and adapted to retract the pawl on movement of the trip lever.

3. A railway safety appliance including a train pipe for conducting compressed air, a branch pipe connected to the train pipe, a valve casing having a chamber connected with the branch pipe, a safety valve movably mounted in the casing for controlling the passage of air through the chamber, the valve having a stem extending out beyond the casing, a supported base, a shaft rotatably mounted on the base and having an arm fixed thereon, the shaft being provided with a latch device and also with a spring for turning the shaft in one direction, an operating rod connected to the arm and extending to the stem for opening the valve, a pawl movably supported on the base and adapted to engage the latch device for restraining action of the spring, and a trip lever pivoted to the base and adapted to engage and retract the pawl on movement of the lever.

4. A railway safety appliance including a train pipe for conducting compressed air, a compressed-air reservoir, a supply pipe connected with the reservoir, a brake valve connected with the supply pipe and the train pipe, a branch pipe connected to the train pipe, a valve casing having a chamber connected with the branch pipe, a safety valve movably mounted in the casing for controlling the passage of air through the chamber, the valve having an operating device, an operating rod movably guided adjacent to the valve casing and adapted to move and open the safety valve, a supported base, a controlling appliance movably mounted on the base and operatively connected to the operating rod, the appliance being provided with

- 6 a latch device and also with a spring for moving the appliance in one direction to operate the operating rod, a pawl movably mounted on the base and adapted to engage the latch device for restraining action of the spring, and a trip lever pivotally connected with the base and adapted to engage and retract the pawl on movement of the trip lever.
- 5 5. A railway safety appliance including an air-brake system having a train pipe for conducting compressed air, a propelling system having a controller lever, a compressed-air reservoir, a brake-valve connected with the train pipe, a supply pipe connected with the reservoir and the brake-valve, a pneumatically operable appliance connected with the lever, a branch pipe connected to the train pipe, two valve casings having each a chamber in each of two portions thereof, one of the chambers of one of the casings being connected to the branch pipe, the remaining chamber having an outlet, a pipe connected with the supply pipe and one of the chambers of the other of the two valve casings, a conducting pipe connected with the remaining chamber of the last-mentioned one of the casings and also with the pneumatically operable appliance, two safety valves movably mounted in the two valve casings respectively for controlling the passage of air through the chambers, and a movably guided operating rod having two devices for simultaneously contacting with the two safety valves to open the valves.
- 10 6. A railway safety appliance including a compressed-air reservoir, a train pipe for conducting compressed air, a supply pipe connected with the reservoir, a brake-valve connected with the supply pipe and the train pipe, a branch pipe connected to the train pipe, a valve casing having a chamber connected with the branch pipe, a safety valve movable in the casing for controlling the passage of air through the chamber and having an operating stem, a supported base, a controlling appliance movably mounted on the base and provided with a latch device, a rod movably supported on the base and having a head thereon, the rod being operatively connected with the appliance, a supported spring in contact with the head under compression for moving the controlling appliance in one direction, a pawl movably mounted on the base and adapted to engage the latch device to restrain action of the spring, a trip lever pivoted to the base and having two cams on opposite sides respectively of the lever pivot for engaging and retracting the pawl, and a connection between the controlling appliance and the stem of the safety valve for opening the valve on retraction of the pawl.
- 15 7. A railway safety appliance including a base, a shaft rotatively mounted on the base and having an arm and also a disk fixed thereon, the disk having a notch in its periphery, a rod connected to the arm and having a head thereon, a supported spring in contact with the head under compression for turning the shaft in one direction, a pawl pivotally supported on the base and adapted to enter the notch to restrain action of the spring, and a trip lever pivoted to the base and having a cam thereon for engaging and retracting the pawl.
- 20 8. In a railway safety appliance, the combination with a train brake pipe, a movable power controlling device, a reservoir for compressed air, a brake valve for admitting air from the reservoir to the brake pipe, and a pneumatically operable appliance connected with the power controlling device adapted for moving the device, of a valve casing having communication at one end with the brake pipe and at its opposite end with the atmosphere, a second valve casing having communication at one end with the reservoir and at its opposite end with the pneumatically operable appliance, two valves movable in the two valve casings respectively and normally seated between their ends to prevent passage of air through the casings, an automatic actuating element, spring actuated operable appliances enabling the element to simultaneously move the two valves from their seats, a lock for restraining the element from acting, and a pivotally supported trip lever having a device for retracting the lock.
- 25 9. In a railway safety appliance, the combination of a frame base having two pairs of shaft bearings and also a spring-box thereon, a shaft rotatively mounted in one of the pairs of bearings and having two arms and also a disk fixed thereon, the disk having a notch in its periphery, a rod pivoted to one of the arms and extending into the spring-box and provided with a head, an actuating spring seated in the spring-box and on said head, a pawl pivotally connected to the base and having a projection to enter the notch for preventing action of the spring, a trip lever pivotally supported by the remaining pair of bearings and provided with a cam device for retracting the pawl, an operable air-controlling valve, and an operating rod pivotally connected to the remaining one of the arms and adapted for operating the valve.
- 30 10. In a railway safety appliance, the combination of a frame base having two abutments on one side thereof provided with two guideways respectively, a shaft rotatively mounted on the opposite side of the base, a disk secured to the shaft and having a notch in its periphery, a pawl pivotally connected with the base and adapted to ride on the disk or to enter the

notch to lock the shaft against rotation in one direction, a lever pivoted to the base and having two cam portions thereon adapted to slide on and retract the pawl from the notch, 5 a rod movably guided in said guideways and having connection with said lever, two springs on said rod seated on said two abutments respectively, two adjusting nuts connected to said rod in contact with the two

springs respectively, and means for turning the shaft when unlocked.

In testimony whereof, we affix our signatures in presence of two witnesses.

JOSEPH F. SEIBOLD.
